AUTOMATIC CONTROL OF REFRIGERATING APPARATUS

Stuart Otto, New York, and Lawrence Bruehl, Brooklyn, N. Y., assignors to Gas Refrigeration Corporation, Scranton, Pa., a corporation of Delaware

Application October 5, 1934, Serial No. 746,940

11 Claims. (Cl. 62—5)

The invention relates to a refrigerating apparatus of the intermittently operating absorption type, and is particularly applicable to small-sized automatically operating apparatus such as are 5 used in household refrigerators.

In an apparatus of this type, there is provided a boiler absorber which, during the heating period, operates as a boiler or still to drive the ammonia or other refrigerating gas from the absorber, and deliver it under pressure to a condenser where it is liquefied, and during the cooling period, operates as an absorber to cause a reduction in pressure by the reabsorption of the 10 gas at reduced pressure and an evaporation of the liquefied gas in the evaporator. The lengths of the successive heating and cooling periods may be controlled in accordance with the temperature of the evaporator, and/or in accordance with the temperature in the boiler absorber, or in various 15 other ways.

One object of the present invention is to provide new and improved means for preventing the heat of the burner or heating element from being radiated or conducted to the storage chamber 20 of the refrigerator during the heating period.

Another object is to provide new and improved means for dissipating the heat from the boiler absorber as promptly as possible after the burner or heating element is turned off, so that absorption may set in as quickly as possible after 25 the end of the heating period.

Another object is to provide an automatic control of the cooling air circulation, which permits the use of a minimum sized condenser, and, if 30 a liquid cooling medium is used for condenser cooling, to permit the use of a minimum sized tank for said medium.

One way in which we may carry out the invention is to provide a casing substantially enclosing 35 the boiler absorber and the burner, and forming a passageway around said boiler absorber for the circulation of air. As a feature of the present invention, the circulation of air through this passageway is controlled by an automatically oper- 40 able valve which is closed during the heating period to prevent undue circulation of air in this passageway except that necessary to maintain combustion from the burner in case combustible gas is used as the heating medium, and which 45 is opened in accordance with certain predetermined conditions, such as the temperature near the boiler absorber to increase the circulation of air through said passageway either by natural air or by forced draft.

50 As another feature of the invention, we provide

another casing substantially encircling and spaced from the first casing to form a second or outer passageway, the circulation of air through said second passageway being controlled by an automatically operable valve which is opened during the heating period, so that the heat radiated or conducted outwardly from the inner passageway will be carried away by the circulation of air through said outer passageway, and is thereby kept away from the storage chamber 5 of the refrigerator. This valve is closed at the end of the heating period so that the major portion of the forced or induced air is permitted to go through the inner passageway and around the boiler absorber to dissipate the heat from 10 15 said boiler absorber.

As another feature of the present invention, we provide a fan which is adapted to assist in the circulation of air around the boiler absorber, and which is automatically controlled in accordance 20 with predetermined phases of the refrigerating cycle.

Various other features and advantages of the invention will be apparent from the following 25 particular description, and from an inspection of the accompanying drawings in which:—

Fig. 1 is a diagrammatic side view, partly in 30 section, of a refrigerator having our improved automatically controlled cooling air circulatory system.

Figs. 2 and 3 are vertical sections showing different forms of automatically controlled cooling 35 air systems.

Fig. 4 is a somewhat diagrammatic view of a system for controlling the operation of a fan and/or a damper in accordance with predetermined phases in the refrigerating cycle.

Fig. 5 is a diagrammatic view showing different 40 positions of the valves of the system shown in Fig. 4 during a complete refrigerating cycle, and

Fig. 6 is a view, somewhat diagrammatic, of another system for controlling the operation of a fan and burner.

The invention may be applied to a single vessel type of boiler or to the double vessel type. In 45 the construction illustrated in Fig. 1, the invention is shown applied to a double vessel type of boiler absorber. In this construction, there is provided a boiler absorber 10 including an upper chamber or vessel 11, and a lower vessel 12. The 50 boiler absorber 10 is shown attached to the rear of a refrigerator storage chamber 13 containing an evaporator 14. Above the boiler absorber 10 and alongside of the storage chamber 13 is a condenser 15. In case the condenser is water 55

cooled, the water tank therefor may be positioned in the position indicated for the condenser.

For heating the boiler absorber 10 there is provided one or more burner tubes 16 disposed directly under the vessel 12 in position to direct the heat therefrom onto said vessel.

The refrigerating system shown is of the usual intermittently operated absorption type in which, during the heating period, the refrigerating medium, such as ammonia, is boiled off from the boiler absorber 10, and delivered to the condenser 15 where it is liquefied and then to the evaporator. When the heating period terminates the boiler absorber is cooled and the liquefied refrigerating medium is evaporated in the evaporator 14, and returned to the boiler absorber 10 where it is reabsorbed.

The connections between the boiler absorber, the evaporator and the condenser, may be the usual ones and have not been illustrated as we claim no novelty in that part of the system.

The boiler absorber 10 is substantially enclosed in a casing 17 which is spaced from the boiler absorber 10 to form an air circulatory passageway 18 around said boiler absorber, and which has the sides thereof substantially following the contour of the sides of the two vessels 11 and 12, so that the hot gaseous products of combustion from the burners 16 will be kept very close to the walls of the boiler absorber. The casing 17 is connected at the top with a flue 19 extending upwardly to an outlet at the top of the refrigerator. The lower end of the casing 17 extends to a position near to or below the burners 16, and is provided with an opening 20 formed between a side wall 21 and a bottom wall 22 of said casing.

Substantially enclosing the casing 17 is an outer casing 23 spaced from the walls of the inner casing 17 and forming therewith a second air circulatory passageway 24 around said casing 17. As shown, the outer rear wall 25 of this outer casing 23 may constitute the rear wall of the refrigerator.

The outer casing 23 has a flue 26 encircling the flue 19 but spaced therefrom, and extending to an outlet at the top of the refrigerator. The inner front wall 27 of the outer casing 23 is spaced from the facing wall of the storage chamber 13 so as to form an air passageway 28 between said chamber and said outer casing 23.

The flues 19 and 26 are disposed towards the rear sides of the casings 17 and 23, and the condenser 15 is disposed between said flues and the rear of the storage chamber 13 to form a passageway 29 around said condenser.

As an important feature of the present invention, the passage of air through the opening 20 of the inner casing 17 is controlled by a valve in the form of a damper 30 which is automatically operable so as to close the opening 20 during the heating period so that substantially all of the heat from the burners 16 is retained in the inner casing 17, and which is moved in open position at the end of the heating period to increase the circulation of air into the inner casing 17 and around the boiler absorber 10 to cool said boiler absorber so that absorption may set in as quickly as possible after the end of the heating period.

In the form shown in Fig. 1, the damper 30 is thermostatically controlled and for that purpose is connected to the bottom wall 22 of the inner casing 17 by a thermostatic bimetallic strip 32 so that the unequal expansion or contraction between the component metals of the strip causes

said strip to curve in accordance with the local temperature conditions. This bimetallic strip is so constructed that during the heating period when the burners 16 are on, the damper 30 is in closed position as shown. As soon as the burners 16 are shut off the lowering of the temperature around the bimetallic strip 32 causes the damper 30 to be moved into open position indicated in dotted lines. The inner casing 17 is provided with apertures 31 to permit the passage of sufficient air into said casing to support combustion from the burners 16 during the heating period if combustible gas is used as the heating medium.

As another feature of the present invention, the circulation of air through the passageway 24 between the two casings 17 and 23 and through the passageways 28 and 29, is controlled by means of the damper 30 and an automatically operable valve in the form of a damper 33. This damper 33 in the form shown in Fig. 1, is thermostatically operated and for that purpose is fixed to the side wall 21 of the inner casing 17 by means of a thermostatic bimetallic strip 34. The damper 33 is advantageously curved to conform with the side portion of the inner casing 17 opposite thereto, so that in open position shown, said damper will be close to said side portion to permit the free passage of air through the two passageways 28 and 29. In closed position indicated in dotted lines, the upper portion of the damper 33 will extend through a slot 35 in the outer casing 23 and transversely through the passageway 28, so that the circulation of air through said passageway 28 and the front side of the passageway 24, is blocked. The passage of air through the rear side of the passageway 24 is advantageously controlled by the damper 30 which, when disposed in open position shown in dotted lines, engages a wall 36 extending transversely from the lower end of the rear wall 25 of the outer casing 23, and thereby blocks the passage of air through said rear side.

The bimetallic strip 34 is so constructed and arranged that when the damper 30 is in open position, at the end of the heating period, the damper 33 is in the position shown in dotted lines to block the passage of air through the passageways 24 and 28. However, when the damper 30 is in closed position, the damper 33 is in position closely adjacent to the walls of the inner casing 17 as shown, so that the passageways 24 and 28 are free to permit circulation of air therethrough.

In the operation of the form of device shown in Fig. 1, at the beginning of the heating period when the burners 16 come on, the local temperatures around the bimetallic strips 32 and 34 are such as to cause the damper 30 to move into closed position and the damper 33 to move into open position as shown and described. During this heating period, the hot gases from the burners 16 may be kept very close to the walls of the boiler absorber 10. The heat absorbed by the inner casing walls will be radiated inwardly towards the boiler absorber 10 so that the heat is effectively applied to the parts to be heated. Some of the heat from the interior of the inner casing 17 will be radiated or conducted outwardly, but it will be carried away by the air which enters the passageway 24 between the two casings 17 and 23. If natural draft is utilized, this air current will be induced by the heating action of the inner flue 19 and also by the ejector action of the inner flue 19. Also, during the heating period, there is induced or created an

air circulation in the passageways 28 and around the condenser 15, so that radiation from the outer casing 23 to the condenser 15 or the storage chamber 13 is minimized during this period.

5 The cooling of the inner casing 17 by the air current between the two casings 17 and 23 is such that even when the boiler absorber is at its highest temperature, there will be very little heat radiated or conducted to the atmosphere of 10 the room from the apparatus. Furthermore, the air drawn through the passageway 24 between the two casings and through the passageway 28 mixes with, dilutes and cools the gases from the flue 19, so that there is the minimum heat radiated to the room from said flue.

15 At the end of the heating period, the burners 16 are turned off. The consequent lowering of the temperature adjacent to the bimetallic strips 32 and 34 causes the opening of the damper 30 and the closing of the damper 33. Under these 20 conditions, air is permitted to circulate freely within the inner casing 17, and around the boiler absorber 10, so that said boiler absorber is quickly cooled and absorption will set in as quickly as 25 possible. The closing of the passageways 24 and 28 during the absorption period causes a larger amount of air to be induced or forced through the inner casing 17.

30 In order to assist in the circulation of air through the various air passageways and flues, a fan 39 may be used as shown, secured to the bottom of the refrigerator and adapted to blow air through the various passageways and flues. The fan may be continuously operated or may 35 be intermittently operated in accordance with the cycle of operation of the refrigerating system, and in accordance with certain features of the invention, as will be more fully described herein-after.

40 In Fig. 2 is shown another form of damper arrangement for controlling the circulation of air through the various passageways and flues. In this construction, the invention is shown as applied to a boiler absorber comprising a single 45 vessel or chamber 40. In this construction, the vessel 40 and burners 16 are substantially enclosed in an inner casing 41 open on its front side, spaced from the walls of said vessel 40 to form an air passageway 42 around said vessel, 50 and having the top wall thereof substantially following the contour of said vessel. This inner casing 41 at the top thereof has a flue 43 which communicates with the passageway 42.

55 Substantially encircling the inner casing 41 is an outer casing 44 spaced from the walls of said inner casing and forming therewith a passageway 45. This outer casing 44 comprises a rear wall 46 and a bottom wall 47, and terminates at its inner side in a tubular extension 48. At the 60 upper end of the outer casing 44 is a flue 49 encircling the flue 43 but spaced therefrom.

65 The circulation of air between the passageways and flues in this construction, is controlled by a pair of automatically operable valves in the form of dampers 50 and 51 cooperating with the open side of the inner casing 41 and thermostatically controlled. For that purpose, the damper 50 is connected to the bottom wall of the inner casing 41 through a bimetallic strip 52, 70 while the damper 51 is bimetallic in its entirety, and is connected to the top wall of said casing.

75 When the burners 16 are on, the temperature adjacent to the thermostatic members 51 and 52 is such as to bring the two dampers together into engagement as shown, so that the open side of the

inner casing 41 is blocked while the passageway 45 between the two casings 41 and 44 is open for the passage of air therethrough. When the burner 16 has been turned off the lowering of the temperature causes the dampers 50 and 51 to move apart and into engagement with the walls of the outer casing 44, as shown in dotted lines, to permit the free entry of air into the inner casing 41 and to block the passage of air in the passageway 45 between the inner and outer casings.

10 In Fig. 3 is shown a construction in which the circulation of air through the various passages is automatically controlled by a single valve in the form of a damper 54. In this construction, 15 the inner casing 55 has a bottom wall 56 and a top wall 57 which substantially follows the general curvature of said boiler absorber, and which is connected to a flue 58, and has on its front side a wall extension 59 extending radially outwardly from its top wall 57 to form an opening 20 between said wall extension and the bottom wall 56.

25 The open side of the inner casing 55 is controlled by the damper 54 connected to one end of a pair of brackets 61 by means of bimetallic strips 62, the other ends of the brackets being connected to the rear wall of said casing. The damper 54 is in the form of a hood having an end wall 63 and a pair of side walls 64 spaced a 30 slightly greater distance than the width of the wall extension 59 so that said damper may swing freely under the action of the thermostatic strips 62.

35 When the burners 16 are on, the damper 54 will be in the position shown, with the end wall 63 thereof extending between the bottom wall 56 and the wall extension 59 of the inner casing, so that the passage of air into the interior of the inner casing 55 is blocked, while the air is permitted to enter the space between the two casings 44 and 55. When the burners 16 are shut off, the damper 54 will be automatically moved in its uppermost position into contact with the wall of the outer casing 44 so as to permit air to enter 45 freely into the interior of the inner casing 55 and to block the upper portion of the inlet end of the passageways between the inner and outer casings. Although the lower portion of the passageway between the inner and outer casings is 50 open in this position of the damper 54, very little air will pass through this lower portion of the passageway at this point, due to the fact that most of the air induced or forced will pass into the interior of the casing 55 as a result of its 55 comparatively larger opening.

60 In Figs. 4 and 5 is shown a unit for automatically controlling the damper and/or the fan according to certain phases in the refrigerating cycle. This feature of the invention is shown as applied to an electrical system in which an electrical burner is used, but as far as certain aspects of this feature are concerned, it may be applied to a system in which combustible gas, steam, hot oil, or other suitable fluid is used as 65 the heating medium. In this construction, there is provided a pair of valves 65 and 66 for controlling the flow of heating medium, such as electric current. These valves 65 and 66 are shown in the form of mercury switches thermostatically controlled from the boiler absorber and evaporator respectively. For that purpose, within the boiler or associated in heat exchange relationship thereto, there is employed a temperature bulb 67 for a fluid medium which will expand 70

and contract with changes in temperature in the boiler absorber, and this is connected to the switch 65 by a suitable operating mechanism 68. In the evaporator, there is employed a similar 5 temperature bulb 70 connected to the switch 66 by the operating mechanism 71. The operating mechanisms 68 and 71 are of the snap type, so that the switches 65 and 66 are held in position between predetermined temperature phases in 10 the boiler absorber and the evaporator.

The current comes in through a pair of main lines 72 and 73, the line 72 having a branch connection 74 to one side of a heating element or burner 75, and a branch connection 74a to one 15 side of the fan 39. The other line 73 comes into the middle contact point of the switch 66.

The right-hand contact point of the switch 66 is connected by means of a line 76 to the right-hand contact point of the switch 65, while the 20 left-hand contact point of the switch 66 is connected to the middle contact point of the switch 65 by means of a line 77. The line 77 is connected to the other side of the fan 39 by means of a line 77a. The left-hand contact point of 25 the switch 65 has a branch connection 78 to the other side of the heating element 75 and another branch connection 79 to one side of an electrically operated mechanism 80 for a damper 81. The other side of this operating mechanism 80 is 30 connected to the branch connection 74a by means of a connection 82.

The operating mechanism 80 may be of any suitable construction. For instance, it may comprise a solenoid 83 having a plunger 84, one 35 end of which is in the form of a rack bar meshing with a toothed wheel 85, the shaft of which carries the damper 81, so that as the circuit through the solenoid 83 is opened or closed the corresponding movement of the plunger 84 causes a 40 movement of the damper 81.

The switches 65 and 66 are so operated as to cause the operation of the fan 39 during the heating period and during a portion of the absorption period, and also causes the operation of the 45 damper 81 coincidentally with the closing and opening of the circuit through the heating element 75.

In Fig. 5 is shown the different positions of the thermostatic switches 65 and 66 during the 50 refrigerating cycle. During the heating period, the switches 65 and 66 are in the position indicated in Fig. 4 and at A in Fig. 5. In this position, the heating element 75 is on, the circuit of the fan 39 is closed, and also the circuit of the 55 electrical operating mechanism 80 so that the damper 81 is closed, and the air is blowing between the inner and outer casings, thereby preventing outward radiation of heat from the inner casing. During this period, there is a comparatively low temperature in the boiler absorber as the gas is passing off freely to the condenser, and there is comparatively high temperature in the evaporator as there is no evaporation or cooling effect taking place.

60 As the heating of the boiler absorber continues, the operation will reach a point at which all of the ammonia or other refrigerant gas has been driven off, and the temperature will rise to such a point in the boiler absorber that the fluid 65 in the temperature bulb 67 in expanding will exert sufficient pressure to cause the reversal of the switch 65 to the position B shown in Fig. 5, while the thermostatic switch 66 remains unchanged. In this position of the switches, the 70 circuit through the heating element 75 will be

opened so that the heat from said element will be shut off. Also, during this phase, the circuit of the electrically operated mechanism 80 will be opened so that the damper 81 will move into position to permit passage of air into the inner casing and around the boiler absorber unit to cool said unit. The temperature of the boiler absorber will then drop and evaporation in the evaporator will begin.

During the middle portion of the absorption period, as the evaporator temperature drops, the pressure of the thermostatic medium in the temperature bulb 70 will decrease sufficiently to cause the switch 66 to reverse into position C shown in Fig. 5, while the switch 65 remains unchanged. 15 In this position, the circuit of the fan 39 will still be closed so that the fan will still be operating while the circuits of the heating elements 75 and the operating mechanism 80 will still be open so that no change takes place in the operation 20 of these members.

During the latter part of the absorption period, the cooling of the boiler absorber unit will cause the switch 65 to move into the position D shown in Fig. 5, while the position of the switch 66 25 remains unchanged. In this position of the switches, the circuit of the fan 39 will be open so that the operation of the fan will be stopped, while the circuit of the damper operating mechanism 80 and the heating element 75 will remain 30 open.

At the end of the absorption period, the temperature of the evaporator will increase sufficiently to reverse the thermostatic switch 66 to the position shown in Fig. 4 and position A shown in 35 Fig. 5, while the switch 65 remains unchanged. In this position of the switches, the circuit of the damper operating mechanism 80, the fan 39, and the heating element 75 will be closed so that these members will be operated and the heating 40 period will begin.

The constructions shown in Figs. 4 and 5 may be applied to the constructions shown in Figs. 1-3 for operating the dampers and the fan.

In Fig. 6 is shown another form of unit for 45 controlling the operation of the fan 39. In this construction the fan 39 may be operated independently of the operation of the heating member or the damper. Also, in this system, gas is used as the heating element. In this construction, the 50 unit comprises a pair of main current lines 86 and 87, one of the lines, as for instance the line 86, including a pair of valves in the form of thermostatic snap switches 88 and 89 controlled by the temperature bulbs 67 and 70 in the boiler 55 absorber unit and the evaporator respectively. The line 86 is connected to one pole of an electrically operated fluid valve 90 controlling the flow through a fluid supply pipe 91, while the other line 87 is connected to the other pole of 60 this fluid valve 90. The supply pipe 91 is connected to a heating element 92 shown in the form of a gas burner, and has a pilot 93 in its line.

Connected across the lines 86 and 87 is the fan 39 and an automatic temperature switch 95 65 disposed in the boiler absorber unit.

In the operation of this system, during the heating period, both switches 88 and 89 are closed so that the circuit of the electrical operating mechanism of the fluid valve 90 is closed, 70 and said valve is opened to permit the passage of gas to the burner 92. As soon as the temperature of the boiler absorber unit has reached a predetermined temperature, the switch 88 is opened while the switch 89 remains closed, so that 75

the circuit of the electrical operating mechanism of the valve 90 is opened and the valve shut. As the temperature in the evaporator reaches its lowest point, the switch 89 is opened. When the temperature in the boiler is lowered to a minimum point, the switch 88 closes, while the switch 89 remains opened. When the evaporator temperature reaches a predetermined point, the switch 89 is also closed, thereby closing the circuit through the electrical operating mechanism of the valve 90, causing the opening of said valve, and permitting the passage of gas to the burner 92, thereby starting the boiling period.

The temperature switch 95 can be so regulated as to effect any desired operation of the fan 39. For instance, it may be so regulated as to operate the fan during the boiling period, and during a portion of the absorption period, or it may be operated only during the absorption period, depending upon the adjustment of the switch 95.

Having thus described our invention, what we claim as new and desire to secure by Letters Patent is:—

1. A refrigerating apparatus of the intermittently operating absorption type, including a boiler absorber, a casing extending around said boiler absorber, spaced therefrom to form a passageway therewith, and having an inlet opening, means for heating said boiler absorber intermittently, a damper extending across said inlet opening, and thermostatic means directly connected to said damper for automatically moving the latter into closed position while said heating means is in operation, and for moving said damper into open position when said heating means is turned off.

2. A refrigerating apparatus of the intermittently operating absorption type, including a boiler absorber, a casing extending around said boiler absorber, spaced therefrom to form a passageway therewith, and having an inlet opening, means for heating said boiler absorber intermittently, a damper extending across said inlet opening, and a bimetallic thermostatic strip connected between said damper and the wall of said casing for moving said damper into closed position while said heating means is in operation, and for moving said damper into open position when said heating means is turned off.

3. A refrigerating apparatus of the intermittently operating absorption type, including a boiler absorber, an inner casing extending around said boiler absorber and spaced therefrom to form a passageway therearound, an outer casing extending around said inner casing and spaced therefrom, means for heating said boiler absorber intermittently, thermostatically operated valve means for controlling the circulation of air between said casings, and separate thermostatically operated valve means for controlling the circulation of air through the inner casing.

4. A refrigerating apparatus of the intermittently operating absorption type, in which the cycle of operation includes a heating period and an absorption period, including a boiler, an inner casing surrounding said boiler and spaced therefrom, said casing being provided with an inlet opening, an outer casing extending around said inner casing and spaced therefrom to form a passageway therewith, a damper for the inlet opening of said inner casing and means thermostatically operable for moving said damper alternately in closed and open position at the beginning and end of the heating period respectively, said damper in open position engaging the outer cas-

ing wall and blocking the passage of at least a portion of the air into the passageway between said casings.

5. A refrigerating apparatus of the intermittently operating absorption type in which the cycle of operation includes a heating period and an absorption period, including a boiler absorber, an inner casing surrounding said boiler absorber and spaced therefrom, said casing being provided with an inlet opening, an outer casing extending around said inner casing, spaced therefrom, and also having an inlet opening, a pair of dampers connected to the wall of said inner casing, and means for automatically controlling said dampers whereby the latter, during the heating period, will be together to block the passage of air into the inner casing, and will be moved apart and into engagement with the outer casing at the end of the heating period to permit free passage of air into said inner casing while blocking the passage of air between said casings.

6. A refrigerating apparatus of the intermittently operating absorption type in which the cycle of operation includes a heating period and an absorption period, including a boiler absorber, a casing around said boiler absorber, a condenser outside of said casing, a fan, means for automatically controlling the operation of said fan, whereby said fan is operated during the heating period and shut off before the end of the absorption period, and automatically operable means for directing the air from said fan only over said condenser to cool the latter during the heating period, and only through said casing during the absorption period to cool said boiler absorber.

7. A refrigerating apparatus of the intermittently operating absorption type, in which the cycle of operation includes a heating period and an absorption period, including a boiler absorber, an evaporator, a heating element for said boiler absorber, a fan, a valve for controlling the circulation of cooling air from said fan and around said boiler absorber, means for operating said valve and said heating element coincidently and intermittently in accordance with temperature conditions in said boiler absorber, and means for operating said fan during the boiling period and a portion of the evaporating period and for shutting off said fan before the end of said absorption period.

8. A refrigerating apparatus of the intermittently operating absorption type in which the cycle of operation includes a heating period and an absorption period, including a boiler absorber, an evaporator, an electric heating element for said boiler absorber, a fan for circulating cooling air, an electrically operated member for controlling the circulation of air around said boiler absorber, and a pair of switches for controlling the passage of electric current to said heating element, to said member, and to said fan, and automatically operable respectively by the temperature in the boiler absorber and the evaporator, whereby said electrically operated valve is operated at the beginning and end of the heating period, and said fan is operated during said boiling period and during a portion of said absorption period, and is turned off before the end of said absorption period.

9. A refrigerating apparatus of the intermittently operating absorption type, including an absorber, a casing around said absorber, and means for circulating cooling air around substantially the entire outer periphery of said casing

during the heating period to minimize the radiation of heat from said casing.

10. A refrigerating apparatus of the intermittently operating absorption type, including an absorber, a casing around said absorber, means for circulating cooling air around substantially the entire outer periphery of said casing during the heating period to minimize the radiation of heat from said casing, and means automatically 5 operable at the end of the heating period for shutting off the circulation of air around said casing and for circulating cooling air in the interior of said casing and around said absorber.

11. A refrigerating apparatus of the intermittently operating absorption type, including a boiler absorber, an inner casing extending around said boiler absorber and spaced therefrom to form a passageway therearound, an outer casing extending around said inner casing and spaced therefrom to form a passageway, and means for circulating cooling air alternately through said inner casing and through the passageway between said casings. 5
